UNITED STATES PATENT OFFICE.

ROBERT D. TOWNSEND, OF CHICAGO, ILLINOIS.

ATTACHMENT FOR CAN-HEADERS.

SPECIFICATION forming part of Letters Patent No. 738,642, dated September 8, 1903.

Application filed December 6, 1902. Serial No. 134,119. (No model.)

To all whom it may concern:

Be it known that I, ROBERT D. TOWNSEND, a citizen of the United States, and a resident of Chicago, in the county of Cook and State 5 of Illinois, have invented a new and Improved Attachment for Can-Headers, of which the following is a full, clear, and exact description.

Heretofore the commercial can-header has 10 been made in as many different sizes as there are different sizes of cans to be manufactured.

The object of this invention is to provide 15 an attachment which may be placed on the machine, thus adapting it to any desired size of can without reorganizing the entire machine. This enables one machine by a very simple adjustment to be adapted to any size of can, and in small factories it will to a great extent reduce the cost of equipping, maintaining, and operating the plant.

The invention is applicable, for example, 20 to machines of that class shown in the patent to Wheaton, No. 477,584, dated June 21, 1902, and which consists in providing for the heads 25 or jaws (see Fig. 5 of the patent above referred to) a ring placed removably in position. By constructing a number of these rings of different internal dimensions, but of equal external dimensions, by merely dis- 30 placing and emplacing the different rings the machine may be changed to operate on cans of different sizes.

This specification is an exact description 35 of one example of my invention, while the claims define the actual scope thereof.

Reference is to be had to the accompanying drawings, forming a part of this specification, in which similar characters of reference indicate corresponding parts in all the views.

40 Figure 1 is a front elevation of the head or jaws referred to above. Fig. 2 is a section thereof on the line 2 2 of Fig. 1. Fig. 3 is a side elevation of the head. Figs. 4, 5, and 6 are elevational views of different sizes 45 of rings, and Fig. 7 is a section on the line 7 7 of Fig. 6.

A indicates the base or main section of the head, having the openings *a* therein, in which are received the supporting-rods. On the 50 main section A the top swinging section B is mounted by means of pivots *b*. These parts A and B have matching semicircular portions

forming a seat for the can end, all of which is commonly known in the art. Now in order to vary the interior area of this seat, so 55 as to suit the heads of cans of various sizes, I provide the sectional ring C, the same being made in sections, so as to be fastened, respectively, to the parts A and B, and when the head is closed these sections form a complete 60 annulus. It is clear that by constructing a number of these rings or annuli of varying internal diameter, but of uniform external diameter, by the mere substitution of one ring for another the machine may be adapted 65 for cans of any size. The ring-sections are removably secured in place, and this is preferably effected by fastening to the sections longitudinally-extending dowel pins or keys 70 *c*, these being held in place by having pins *c'* passing transversely across the dowels and into the rings. The sections A and B of the head are recessed, as indicated at *a'* and *b'*, respectively, so that the pins or dowels *c* may be fitted snugly therein. This will hold the 75 rings securely in place, yet permit their ready removal by withdrawing the sections axially of the head. In order further to secure the rings in place, fastening-screws *E* are provided, these being passed through the sec- 80 tions A and B and engaged with the ring-sections, as indicated in Fig. 1.

The form of the invention here shown illustrates a header for round cans. It is obvious that the invention can be used equally on 85 cans of angular forms, and it should be understood that the term "ring" as herein employed is intended to embrace constructions for cans of any cross-sectional shape.

Various changes in the form, proportions, 90 and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. In a can-header, the combination with the head or jaws, of a ring adapted to be 100 fitted therein, and dowel-pins fastened to the ring and adapted to engage the head, removably to hold the ring in place, said dowel-pins being secured to the outside of the ring

and extending parallel therewith and the said head being recessed to receive the projected portions of the dowel-pins.

2. A can-header, having a head or jaws, a plurality of rings of equal exterior and of varying interior diameter, for the purpose specified, any one of said rings being capable of fitting securely in the head or jaws, and dowel-pins fastened to the outer sides of the ring and adapted to engage the head or jaws removably to hold the rings in place, said

dowel-pins extending parallel with the axes of the rings, and the head or jaws being recessed to receive the projecting portions of the dowel-pins.

In testimony whereof I have signed my name to this specification in the presence of two subscribing witnesses.

ROBERT D. TOWNSEND.
